UNITED STATES PATENT OFFICE.

EDWIN G. MUMMERY, OF DETROIT, MICHIGAN.

HYDROCARBON BURNER.

1,410,214.

Specification of Letters Patent. Patented Mar. 21, 1922.

Application filed December 27, 1920. Serial No. 433,434.

To all whom it may concern:

Be it known that I, EDWIN G. MUMMERY, a citizen of the United States, and residing at Detroit, in the county of Wayne and State of Michigan, have invented a new and Improved Hydrocarbon Burner, of which the following is a specification.

This invention relates to hydrocarbon burners comprising troughs or channels 10 wherein the liquid fuel may be evaporated and concentric walls constituting combustion chambers extending up from the evaporators and provided with openings to admit sufficient air to insure complete combustion 15 of the fuel, and the object of this invention is to provide a burner of this character with a plurality of burner rings so it shall be of sufficient operating capacity for hot air furnaces, hot water heaters and 20 steam boilers.

This invention consists in the construction, arrangement and proportions of the various parts of the improved duplex hydrocarbon burner illustrated in the accompanying drawings and particularly pointed out in the claims, and in the combination therewith of a preheater mounted on the outside of one of the evaporators to so raise the temperature thereof that liquid fuel 25 flowing into said evaporator immediately becomes vaporized and inflammable.

In the accompanying drawings, Fig. 1 is a plan of a hydrocarbon burner embodying my present invention. Fig. 2 is a section 35 on the line 2—2 of Fig. 1. Fig. 3 is a section on the line 3—3 of Fig. 2. Fig. 4 is a plan of a portion of the burner base. Fig. 5 is an elevation of this improved burner. Fig. 40 6 is a sectional view showing an electric heater in position.

Similar reference characters refer to like parts throughout the several views.

The ordinary hydrocarbon burners used in cook stoves are of such small size and 45 limited capacity that a wick of asbestos in the evaporating trough, when saturated with the liquid fuel, furnishes sufficient heat when ignited to so raise the temperature of the several parts of the burner ring that the 50 fuel becomes vaporized as it enters and burns freely, the temperature of the burner being kept up by this combustion.

But where a burner sufficiently large for 55 a furnace is formed with several concentric combustion chambers, each built up of heavy cast iron rings, this internal preheating by

the normal fuel of the burner becomes impossible, and the adoption of burners sufficiently large for furnaces has probably been delayed for this reason. I have found that 60 when several concentric combustion chambers are employed, the trough of that chamber which receives the liquid fuel acts as the evaporator for the entire burner and that, furthermore, an independent heater adjacent thereto of sufficient capacity to raise the evaporator to fuel-vaporizing temperature 65 solves the problem presented by the very heavy burner structure which may be eight inches and upwards in diameter and weigh 70 twenty-four pounds and upward.

It is evident that any available preheater may be employed, and I have shown one adapted for gas and another for electricity. After the fuel begins to vaporize under this 75 externally applied heat, it may be ignited by dropping a lighted match into the pre-heated combustion chamber or by introducing a bit of burning fibre on a wire.

The drawings show a burner having a 80 base 1 comprising two concentric evaporator channels or troughs 2 and 3, the inner having walls 4 and 5 and the outer wider channel having walls 6 and 7, a cover ring 8 being provided to rest on a ledge 9 of the 85 outer wall 7 to support the outer chimney. This outer wall or chimney is formed of any desired number of sections, two marked 11 and 12 being shown, each formed with slits 13 which extend through the walls to admit 90 air to the combustion chamber between the walls. Integral ribs 14 hold together the several narrow rings composing these sections. The lower section 12 has a flange 15 extending below the cover ring 8. The edges 95 of contacting sections and of the walls of the channels or troughs are made reciprocal, that is, so that they will have engaging surfaces in different planes which are at an angle to each other.

The inner wall or chimney of the outer burner rests on the wall 6 of the channel 3 and also consists of circumferentially slotted sections 16 and 17. I prefer to form the wall 6 with holes 18 to admit air. Concentric with the walls of the outer combustion chamber are the walls of the inner combustion chamber, the outer wall of the inner chamber being formed of the circumferentially slotted sections 18 and 19 which rest 110 on the wall 5 of the channel 3, while the similar sections 21 and 22 of the inner wall

rest on the wall 4 of this channel. A ring 23 closes the space between the inner and outer combustion chamber and forces the air between them to enter the combustion chambers through the openings in their walls.

Radial ducts 24 connect the two evaporators and the fuel is conducted to either one of the channels by any desired means, but for convenience I prefer to conduct the fuel to the outer channel 3 by means of a tube 25, the wall 7 being bulged out at 26, as shown in Fig. 4, to permit the fuel to flow evenly into the channel and not be thrown against one spot on the lower edge of the flange 15 of the section 12 which is normally very hot.

The distance between the walls 4 and 5 of the inner burner ring is less than that between the walls 6 and 7 of the outer burner ring in order that the flame from the two rings shall rise to about the same height. I have found that when these combustion chambers are of the same width that the flame from the inner ring is liable to be yellow and to rise much above the clear blue outer flame.

An inner tube 27 has a radial flange 28 which rests on the top of the upper section 21 of the inner burner ring and not only conducts air to the slits in the inner wall thereof but permits free flow of air from below the burner through the center thereof. A hood 29 is provided with feet 30 which rest on the cover-plate 8, or with any other desired support and this hood conducts any vaporized fuel which may have escaped from the outer evaporator 3 to the slits 13 in the sections 11 and 12.

I prefer to form the walls of the combustion chambers in sections as the intense heat at the tops of these walls has a tendency to warp these tops in time and thus destroy the usefulness of these walls. A new section can be substituted for an old one in a very few minutes and at little expense.

Because of the large amount of metal in the evaporators and in the walls of the burner rings, the asbestos wicks commonly used to preheat the burners are of no value in the present structure. I have found that it is necessary to supply independent means for preheating the channel which acts as the evaporator and which receives the liquid fuel (usually the outer channel) and have further found that a simple burner tube 32 of ring shape with openings 33 for the jets of gas is admirably suited to this purpose. Gas may be conducted from the house mains to this burner ring by a pipe 34 and may be controlled by the valve 35.

Gas being turned on and ignited, the evaporator 3 soon becomes sufficiently hot to vaporize the fuel kerosene or a large part of the crude oil when that is used. The fuel vapor is then ignited and burns between the

walls of the outer ring, heating the evaporator 3 to a high temperature. The pre-heater is cut off as soon as the burner begins to function. The liquid fuel entering through the pipe 25 flows along the channel 3 outside of the depending flange 15 and soon becomes vaporized, the vapors flowing in below the flange 15 quite evenly entirely around the burner. The advantage of this flange 15 is that it holds back the vapor in the space outside of it, and causes a slight pressure to occur within such space which causes the fuel vapor to flow through beneath this flange very evenly and thus produces a very even flame in the several burner rings. Streams of fuel vapor flow across to the inner channel through the conduits 24 and up between the walls of the inner burner ring until they ignite at the top thereof from the flame of the outer burner ring.

I have shown posts 37 to support the pre-heater 32 and the base 1, the preheater having perforated lugs 38 resting on the lower largest portions of these posts and the base 1 having perforated lugs 39 which receive the reduced upper ends of these posts. Three posts are preferred.

In some cases a preheater comprising an annular casing 42 in which are the electric heating elements 43 may be preferred. The ordinary house current may be used for this purpose. A backing 44 of asbestos prevents loss of heat. The usual insulation will be employed. Any desired means (not shown) may be employed to hold this heater in position.

While I have shown and prefer circular troughs because of the uniformity of the resultant flame, I do not wish to be limited thereto, as any other form desired may be employed. The details and proportions of the several parts of this burner may all be changed by those skilled in the art without departing from the spirit of my invention as set forth in the following claims.

I claim:

1. A hydrocarbon burner comprising a base embodying a plurality of circular channels and foraminous cylindrical walls extending up from the channels each wall comprising superimposed alined sections, and each section consisting of spaced parallel coaxial rings and longitudinal ribs integral with the rings and uniting them into sections.

2. A hydrocarbon burner comprising a base embodying a plurality of circular channels and foraminous cylindrical walls extending up from the channels each wall comprising superimposed alined sections, and each section consisting of spaced parallel coaxial rings and longitudinal ribs integral with the rings and uniting them into sections, the spaces between the walls con-

stituting combustion chambers and the distance between the walls of the inner combustion chamber being less than that between the walls of the outer combustion chamber.

5. A hydrocarbon burner comprising a base embodying a plurality of circular channels and cylindrical walls extending up from the channels to constitute combustion chambers, and a fuel supply tube connecting to the outer wall of one of the channels, said outer wall being bulged out at the point of connection.

10. A hydrocarbon burner comprising a base embodying a plurality of circular channels and foraminous cylindrical walls extending up from the channels, each foraminous wall comprising a plurality of sections, the engaging ends of the sections being respectively circumferentially shouldered and 20 recessed to hold them alined.

15. A hydrocarbon burner comprising a

base embodying a plurality of circular channels of which the outer is wider than the inner, a cover ring extending over the outer portion of the outer channel, cylindrical walls extending upward in pairs from the several channels and constituting burners therewith, the outer wall of the outer burner resting on said cover ring and having a flange extending down below said cover ring to cause a pressure of fuel vapor within the channel outside of said flange.

25. A hydrocarbon burner comprising a plurality of burner rings each embodying a channel and two foraminous walls, one of the channels constituting a fuel evaporator, conduits connecting the channels, a ring closing the space between the adjacent walls of adjacent burners, a cylindrical imperforate wall inside the inner burner ring and a flange extending radially outward therefrom to the adjacent wall of the inner burner.

30. 40. EDWIN G. MUMMERY.
